(57) **CLAIM**

We claim the ornamental design for a display screen or portion thereof with graphical user interface, as shown and described.

DESCRIPTION

FIG. 1 is a front view of a first embodiment of a display screen or portion thereof with graphical user interface showing our new design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a six embodiment thereof;

FIG. 7 is a front view of a seventh embodiment thereof;

FIG. 8 is a front view of an eighth embodiment thereof;

FIG. 9 is a front view of a ninth embodiment thereof;

FIG. 10 is a front view of a tenth embodiment thereof;

FIG. 11 is a front view of an eleventh embodiment thereof; and,

FIG. 12 is a front view of a twelfth embodiment thereof.

The outer perimeter broken lines in the drawings represent a display screen or portion thereof and form no part of the claimed design. The remaining broken lines in the drawings illustrate portions of the graphical user interface that form no part of the claimed design.
